DOOR INTERLOCK MECHANISM FOR
ENCLOSED CIRCUIT BREAKERS

Harris I. Stanback and Harry W. Curtis, both of Lexington, Ky., assignors to Square D Company, Park Ridge, Ill., a corporation of Michigan

Filed Nov. 10, 1961, Ser. No. 151,542
9 Claims. (Cl. 200—50)

This invention relates generally to enclosed electrical circuit breakers and more particularly to an interlock mechanism between the operating handle of an electrical circuit breaker and the door of an enclosure box therefor.

An object of the invention is to provide an improved defeatable interlock mechanism for preventing unintentional or unauthorized opening of an enclosure door when a handle of a circuit breaker within the enclosure is in the "on" or circuit-closed position.

Another object is to provide an improved defeatable interlock mechanism for preventing unintentional or unauthorized opening of either of two enclosure doors of an enclosure containing two circuit breakers when the handle of the associated circuit breaker is in "on" position.

A further object of the invention is to provide an improved defeatable circuit breaker handle-enclosure door interlock mechanism having a slide on the door cooperable with the circuit breaker handle and lockable in either "on" or "off" position.

A still further object is to provide the combination of an enclosure adapted to house a pair of circuit breakers arranged in end-to-end relationship, the enclosure having a pair of front doors hinged thereto at their remote ends and opening in opposite directions from their adjacent ends, a pair of handle members reciprocably mounted respectively in the doors for movement toward and away from each other, the handle members being operatively associative with operating handles of the circuit breakers and having plate members secured thereto on the inner sides of the doors, and an interlock latch member rotatably mounted between the adjacent ends of the plate members and associative with and dissociable from the plate members by reciprocal movement of the handle members and also by rotary movement of the interlock latch member.

Other objects will become apparent from the following specification and the accompanying drawings in which:

FIGURE 1 is a perspective view of a circuit breaker enclosure constructed in accordance with this invention;

FIGURE 2 is a plan view of the enclosure of FIGURE 1 with portions thereof broken away;

FIGURE 3 is a sectional view in side elevation taken generally as indicated by the line 3—3 of FIGURE 2;

FIGURE 4 is a fragmentary sectional plan view taken generally along the line 4—4 of FIGURE 5;

FIGURE 5 is a fragmentary sectional view in front elevation taken generally along the line 5—5 of FIGURE 4;

FIGURE 6 is an exploded perspective view of certain portions of the enclosure;

FIGURE 7 is a fragmentary sectional view in side elevation taken generally along the line 7—7 of FIGURE 1; and

FIGURE 8 is a fragmentary sectional view in side elevation taken generally along the line 8—8 of FIGURE 1.

The enclosure or box 10 includes a top 11 identical with a bottom 12 and a left side 13 identical with a right side 14. The sides are provided with rear mounting flanges 15 and 16, respectively, and with wiring access holes indicated by numerals 17 and 18, respectively. The box 10 is open at the back and is closed at the front by

2

left and right hand front cover doors 19 and 20. The front edge portions of the top 11 and the bottom 12 are inwardly offset as shown in FIGURES 3, 7, and 8 and are respectively overlapped by upper and lower flanges on the doors 19 and 20.

As shown in FIGURE 1, a flange 24 at the outer end portion of the door 20 is connected to the right side 14 of the box 10 by a pair of hinges 25 and 26, an open position of the door 20 being indicated in FIGURE 2 by broken lines. The front edge portion of the right side 14 is formed similarly to the front edge portion of the left side 13, which is inwardly offset as shown in FIGURE 2, the offsetting portion being provided with a pair of slots, only one of which is shown, for respectively receiving one portion of each of a pair of hinges similar to the hinges 25 and 26, said portions being secured to the inner surface of the side 13. The other portions of said pair of hinges are respectively secured to the inner surface of a flange 21 at the outer end portion of the door 19, the flange 21 being provided with a pair of recesses 22 and 23, as shown in FIGURE 6, to receive the mating parts of the hinges.

As shown in FIGURES 2 and 3, a pair of channel-shaped brackets 29 and 30 is welded inside the box 10 adjacent the respective sides 13 and 14, the opposite sides of the channels being welded to the top 11 and the bottom 12 of the box, respectively. An insulating base 31 is suitably secured to the brackets 29 and 30 as by screws 32 threaded into tapped holes in the brackets.

By way of example, a pair of three-pole electrical circuit breakers 34 and 35 is mounted within the box 10. The outer ends of the circuit breakers are respectively secured to a pair of brackets 36 and 37 by means such as screws 38 threaded into tapped holes in the brackets, which in turn are secured to the base 31 by means such as screws 39. As will be understood, the outer ends of the circuit breakers 34 and 35 are provided with electrical connectors (not shown) for each pole for receiving the ends of electrical conductors (not shown) leading to an electrical load through one of the wiring access holes 17 and 18. At the inner ends of the circuit breakers, the respective poles are electrically connected through various strap conductors or branch bus bars, which are secured to the base 31 and shown in broken lines in FIGURE 2, to respective terminal jaws 40 adapted to plug onto main cylindrical bus bars (not shown).

A handle member 41 is reciprocably mounted in a generally rectangular mounting slot 42 (FIGURES 4 and 6) provided in the door 19 and has a flanged plate member 43 provided with an open-ended slot 53 secured thereto from the inner side of the door 19 by means such as screws 44 threaded into bosses 45 provided on the inner end of the handle member. The door 19 has "on" and "off" indicia thereon as shown in FIGURES 1 and 6, and the handle member 41 has extensions 47 and 48 thereon on the outer side of the door, the arrangement being such that in the two extreme positions of the handle member within the slot 42, one of the indicia is completely covered and the other is completely uncovered. Further, the flanged plate member 43 is provided with an aperture 57 and the handle member 41 is hollow and is open to the inside of the box 10 for receiving a pivotable operating handle 49 of the circuit breaker 34, and when the door 19 is closed, the indicia on the outer side of the door indicate whether the operating handle 49 of the circuit breaker is in its "on," "off," or "tripped" position, the "tripped" position being indicated by another indica (not shown) above the center of the slot 42 corresponding to a position of the handle member 41 in which the "on" and "off" indicia are each partially cov-

ered and partially uncovered. The handle member 41 is provided with a pair of continuous beads 46 to reduce frictional engagement between the door 19 and the extensions 47 and 48.

The door 19 is provided with a slot through which extends a leg 51 of an angle bracket 52, the other leg 53 being secured to the inner side of the door by means such as welding. Further, the handle member 41 is provided with a lower locking flange 54 having a plurality of apertures 55 therethrough alignable with a plurality of apertures 56 provided in the leg 51 for the reception of padlocks by which the handle member 41 may be locked in either "on" or "off" position to secure the operating handle 49 of the circuit breaker 34 in a corresponding position.

The door 19 is also provided with a slot 59 (FIGURES 4 and 6) for receiving a spring biased padlock latch 60 pivotally mounted on the top 11 of the box 10 by a rivet 62 and having a hole 61 therethrough for reception of a padlock. When the door 19 is locked shut and the handle member 41 is locked in position, the position of the operating handle 49 of the circuit breaker 34 cannot be changed.

A pair of mounting angle brackets 64 and 65 is secured to the top 11 and the bottom 12, respectively, of the box 10 by means such as welding. A tang 66 is provided on the horizontal portion of the bracket 64 to retain an end of a compression spring 67, the other end of the spring 67 bearing against a bent tab 68 provided on the latch 60. The latch 60 is also provided with a latching surface 69. When the door 19 is closed and the latch 60 first enters the slot 59, the leading edge of the latch 60 engages the left edge (FIGURE 4) of the slot 59 and the latch 60 is pivoted counter-clockwise on the rivet 62 as the spring 67 is compressed. As the door 19 passes the latching surface 69, the spring 67 rotates the latch 60 clockwise and the latching surface 69 engages the door 19 adjacent the left edge of the slot 59 to retain it in closed position. The latch 60 may be manually pivoted to disengage the latching surface 69 from the door 19 when it is desired to open the door.

Secured to the vertical portions of the brackets 64 and 65 by means such as screws 71 is a larger channel-shaped bracket 72 having a bottom 73, sides 74 and 75, and outwardly extending flanges 76 and 77 on the free ends of the sides 74 and 75, respectively, the screws 71 extending through the flanges 76 and 77, respectively, and being threaded into the brackets 64 and 65, respectively.

A sheet of insulating material 80 having bent over edges 31 and 32 is secured to the inner side of the bracket 72, as best shown in FIGURE 7, by means such as a non-conducting screw 83 threaded into the upper portion of the flange 76 and a similar screw 84 threaded into the lower portion of the flange 77, the screws 83 and 84 preferably being formed of a material such as nylon.

The sides 74 and 75 and the outer edges of the bottom 73 of the bracket 72 are cut away to provide slots indicated by numerals 87 and 88, respectively. An interlock latch member 90, shown best in FIGURES 5 and 6, is pivotally mounted on the inner side of the bottom 73 of the bracket 72 by means of a rivet 91 having an outer slotted head adapted to receive the tip of a screwdriver. The rivet 91 is pivotable in a round hole in the bottom 73 of the bracket 72, but is provided with a reduced diameter portion at its inner end (FIGURE 8) which is swaged into a square hole in the interlock latch member 90 to key the latch member 90 to the rivet.

An inwardly projecting tang 92 (FIGURE 5) is provided on the side 75 of the bracket 72 and an offset tang 93 is provided on a lower portion of the interlock latch member 90 for the mounting of a compression spring 94 which biases the latch member 90 clockwise in FIGURE 5, an upper portion of the latch member 90 engaging a stop in the form of the portion of the side 75 of the bracket 75

72 immediately above the slot 88. The interlock latch member 90 may be pivoted through a limited arc of movement counter-clockwise in FIGURE 5 against the force of the spring 94 by rotation of the rivet 91 with a screw driver, the movement being limited by engagement of the upper portion of the latch member 90 with the portion of the side 74 of the bracket 72 immediately above the slot 87.

The interlock latch member 90 has an arm 95 extending outwardly of the slot 87, a bent projection or interfering portion 96 being formed on an edge of the outer end thereof.

In FIGURES 4 and 5, the handle member 41 and the operating handle 49 are shown in "off" position wherein the flanged plate member 43 and the projection 96 on the arm 95 of the interlock latch member 90 are in a non-interfering relationship to each other and the door 19 may be opened upon release of the latch 60. When the handle member 41 and the operating handle 49 are moved to the right to "on" position, the flanged plate member 43 will be shifted to the dotted line position thereof indicated in FIGURE 5 wherein the projection 96 and the portion of the flanged plate member above the open-ended slot 50 are in an interfering relationship to each other and the door 19 cannot be opened merely upon the release of the latch 60. However, an authorized person desiring to open the door 19 when the handle member 41 and operating handle 49 are in "on" position may do so after first rotating the interlock latch member 90 counter-clockwise to lower the projection 96 into alignment with the slot 50.

The operation described above with respect to the door 19 is equally applicable with respect to the door 20, for which a complete separate description of cooperating parts and of the operation is omitted. It will be sufficient to point out that the door 20 is provided with a handle member 41a, a plate member 43a, and a latch 60a corresponding to the handle member 41, the plate member 43, and the latch 60 of the door 19, and further that the interlock latch member 90 has an arm 95a and projection 96a corresponding to the arm 95 and projection 96. The plate member 43a, shown in FIGURE 2 in broken lines, is provided with a slot corresponding to a slot 50a shown in the plate member 43 in FIGURES 5 and 6, and rotation of the interlock latch member 90 dissociates the projections 96 and 96a from the plate members 43 and 43a respectively.

Various modifications may be made in the structure disclosed without departing from the spirit and scope of the invention as set forth in the appended claims.

We claim:

1. The combination comprising:
  - (a) a box adapted to house an electrical circuit breaker mountable therein,
  - (b) said box having a front cover door connected thereto by a hinge,
  - (c) said door having an elongated generally rectangular mounting slot therein,
  - (d) a handle member slidably mounted in said mounting slot and operable from an outer side of said door for sliding movement toward and away from said hinge,
  - (e) a plate member secured to said handle member on an inner side of said door for sliding movement with said handle member,
  - (f) said plate member having an aperture therethrough and said handle member being hollow and open toward the inside of said box to receive a pivotable operating handle of said electrical circuit breaker when said electrical circuit breaker is mounted in said box, whereby said operating handle may be operated by sliding movement of said handle member, and
  - (g) an interlock latch member mounted in said box

adjacent an end of said plate member remote from said hinge,

(h) said interlock latch member having an interfering portion located between said plate member and the inner side of said door and engageable with a portion of said plate member to interfere with opening of said door when said handle member is in a position adjacent an end of said mounting slot remote from said hinge, and

(i) said interfering portion of said interlock latch member being spaced from said plate member in a direction away from said hinge to permit opening of said door without interference when said handle member is in a position adjacent an end of said mounting slot adjacent said hinge.

2. The combination comprising:

(a) a box adapted to house an electrical circuit breaker mountable therein,

(b) said box having a front cover door connected thereto by a hinge,

(c) said door having an elongated generally rectangular mounting slot therein,

(d) a handle member slidably mounted in said mounting slot and operable from an outer side of said door for sliding movement toward and away from said hinge,

(e) a plate member secured to said handle member on an inner side of said door for sliding movement with said handle member,

(f) said plate member having an aperture therethrough and said handle member being hollow and open toward the inside of said box to receive a pivotable operating handle of said electrical circuit breaker when said electrical circuit breaker is mounted in said box, whereby said operating handle may be operated by sliding movement of said handle member,

(g) said plate member having an open-ended slot therein adjacent an end thereof remote from said hinge, and

(h) an interlock latch member pivotally mounted in said box adjacent the end of said plate member having said open-ended slot therein,

(i) said interlock latch member having an interfering portion located between said plate member and the inner side of said door and engageable with a portion of said plate member adjacent said open-ended slot to interfere with opening of said door when said handle member is in a position adjacent an end of said mounting slot remote from said hinge,

(j) means for pivoting said interlock latch member from outside said box to move said interfering portion into alignment with said open-ended slot and permit opening of said door without interference even though said handle member is in said position adjacent said end of said mounting slot remote from said hinge, and

(k) said interfering portion of said interlock latch member being spaced from said plate member in a direction away from said hinge to permit opening of said door without interference when said handle member is in a position adjacent an end of said mounting slot adjacent said hinge.

3. The combination claimed in claim 2, including biasing means urging said pivotally mounted interlock latch member toward a position wherein it is out of alignment with said open-ended slot in said plate member.

4. The combination claimed in claim 2, including stop means limiting pivotal movement of said interlock latch member in opposite directions.

5. The combination claimed in claim 2, including a spring-biased padlock latch pivotally mounted in said box and extending outwardly thereof, and wherein said door is provided with a slot for receiving an outer end of said padlock latch, said outer end of said padlock latch hav-

ing a hole therethrough for reception of a padlock by which said door may be locked closed.

6. The combination claimed in claim 2, including padlock attaching means on said handle member and door adapted to receive a padlock for locking said handle member against movement with respect to said door.

7. The combination comprising:

(a) a box adapted to house a pair of electrical circuit breakers mountable therein,

(b) said box having a pair of front cover doors connected respectively thereto adjacent opposite ends thereof by a pair of hinges,

(c) said doors having a pair of mounting slots respectively therein,

(d) a pair of handle members reciprocably mounted respectively in said mounting slots in said doors, each handle member being operable from an outer side of its respective door for movement toward and away from the hinge of its respective door,

(e) a pair of plate members, each plate member being secured to one of said handle members on an inner side of its respective door,

(f) each of said plate members having an aperture therethrough and each of said handle members being hollow and open toward the inside of said box to receive a pivotable operating handle of one of said electrical circuit breakers when said electrical circuit breakers are mounted in said box, whereby the operating handles of the circuit breakers may be respectively operated by said handle members, and

(g) each of said plate members having an open-ended slot therein adjacent an end thereof remote from the hinge of its respective door,

(h) and an interlock latch member pivotally mounted in said box between said plate members,

(i) said interlock latch member having a pair of interfering portions each located between one of said plate members and the inner side of its respective door and each engageable with a portion of its respective plate member adjacent the open-ended slot therein to interfere with the opening of its respective door when its respective handle member is in a position adjacent an end of its respective mounting slot remote from its respective hinge,

(j) means for pivoting said interlock latch member from outside said box to move each of said interfering portions into alignment with the open-ended slot in its respective plate member and permit opening of its respective door without interference even though its respective handle member is in said position adjacent an end of its respective mounting slot remote from its respective hinge, and

(k) each of said interfering portions of said interlock latch member being spaced from its respective plate member in a direction away from its respective hinge to permit opening of its respective door without interference when its respective handle member is in a position adjacent an end of its respective mounting slot adjacent its respective hinge.

8. The combination comprising:

(a) an enclosure adapted to house a pair of circuit breakers mountable therein in end-to-end relationship with operating handles thereof extending toward the front of said enclosure,

(b) said enclosure having a pair of front doors hinged thereto at their remote ends and opening in opposite directions from their adjacent ends,

(c) a pair of handle members respectively slidably mounted on said doors for movement toward each other to a first position and away from each other to a second position,

(d) said handle members being operatively connected respectively to said operating handles of said circuit breakers when said circuit breakers are mounted in

said enclosure and having a pair of plate members secured respectively thereto on the inner sides of said doors for sliding movement with said handle members, and

(e) an interlock latch member rotatably mounted in said enclosure between adjacent ends of said plate members for rotary movement between first and second positions independently of the positions of said handle members and having a pair of interfering portions respectively interfering with said plate members to prevent opening of said doors when said handle members are respectively in said first positions thereof and said interlock latch member is in said first position thereof, the interfering relationship between said interlock latch member and said plate members being changeable to a non-interfering relationship by movement of said handle members respectively to said second positions thereof while said interlock latch member remains in said first position thereof and also by rotary movement of said interlock latch member to said second position thereof while said handle members remain respectively in said first positions thereof.

9. The combination comprising:

- (a) an enclosure adapted to house a circuit breaker 25 mountable therein with an operating handle thereof extending toward the front of said enclosure,
- (b) said enclosure having a front door connected thereto by a hinge,
- (c) a handle member slidably mounted on said door 30 for movement away from said hinge to a first position and toward said hinge to a second position,

(d) said handle member being operatively connected to said operating handle of said circuit breaker when said circuit breaker is mounted in said enclosure and having a plate member secured thereto on the inner side of said door for sliding movement with said handle member, and

(e) an interlock latch member rotatably mounted in said enclosure adjacent an end of said plate member remote from said hinge for rotary movement between first and second positions independently of the position of said handle member and having an interfering portion interfering with said plate member to prevent opening of said door when said handle member and said interlock latch member are respectively in said first positions thereof, the interfering relationship between said interlock latch member and said plate member being changeable to a non-interfering relationship by movement of said handle member to said second position thereof while said interlock latch member remains in said first position thereof and also by rotary movement of said interlock latch member to said second position thereof while said handle member remains in said first position thereof.
